United States Patent Office

Des. 225,973

Patented Jan. 16, 1973

225,973

BOTTLE OR THE LIKE

Robert Setrakian, 21 Turnagain Road,
Kentfield, Calif. 94904

Filed May 26, 1971, Ser. No. 147,307

Term of patent 14 years

Int. Cl. D9—01

U.S. Cl. D9—72

FIG. 2

FIG. 1

FIG. 3

FIG. 4

FIG. 5

FIG. 1 is a front elevational view of a bottle or the like showing my new design;

FIG. 2 is a rear elevational view;

FIG. 3 is a side elevational view looking from the left of FIG. 1;

FIG. 4 is a top plan view; and

FIG. 5 is a bottom plan view.

I claim:

The ornamental design for a bottle or the like, as shown.
